RIVET REMOVING DEVICE

Harry D. Rocheville, Los Angeles, Calif., assignor
to Consolidated Vultee Aircraft Corporation,
San Diego, Calif., a corporation of Delaware

Application August 29, 1945, Serial No. 613,378

6 Claims. (Cl. 164—94)

1

The present invention relates to devices for removing rivets.

Heretofore it has been customary to remove a rivet from the plates to which it is applied by placing against the preformed or upset head of the rivet a drill having substantially the same diameter as the shank of the rivet, and then rotating and exerting pressure on the drill in order to drill through the rivet and sever from the shank of the rivet the head against which the drill is placed. In practice it has been found that this method of removing a rivet is objectionable because in connection with drilling of the rivet it is very difficult to hold the drill in coaxial relation with the shank, and hence the drill produces in the plates oversized or irregularly shaped holes which preclude the use of a new rivet of the same size as the removed rivet. The aforementioned method is also objectionable because it requires considerable time and consequently is costly.

The primary object of the invention is to provide a rivet removing device which is an improvement upon, and eliminates the objections of, previously designed and used devices for the same purpose, operates by way of percussion or hammering, and is characterized by the fact that it will, when properly used, quickly remove a rivet without enlarging or distorting the rivet receiving holes in the riveted plates. In general the subject device comprises an arbor having one end thereof adapted for connection to the operating end of a standard or conventional rivet gun and its other end provided with a cylindrical coaxial cutting tool, the outer end of which has an annular cutting edge which is adapted to be placed in centered relation with the preformed head of the rivet to be removed and operates in response to actuation of the rivet gun to sever the outer portion of the preformed head from the rivet shank and eject the shank from the holes in the riveted plates.

Another object of the invention is to provide a rivet removing device of the aforementioned type in which the outer end of the cylindrical cutting tool on the arbor embodies a pilot point which is disposed centrally within the annular cutting edge and is adapted when the device is used to remove a rivet having a so-called dimple in the center of its preformed head to fit within the dimple and thus hold the annular cutting edge in centered relation with the preformed head, or when the device is used to remove a rivet having no dimple in its preformed head to form a dimple in the head and thus maintain the an-

2

nular cutting edge in proper relation with the head during a rivet removing operation.

Another object of the invention is to provide a rivet removing device of the type and character under consideration which comprises in addition to the arbor, means for automatically retracting the arbor after a rivet removing operation.

A further object of the invention is to provide a rivet removing device of the last mentioned character in which the arbor retracting means is in the form of a spring loaded sleeve-like jacket which fits slidably around the tool carrying end of the arbor and has at its front or outer end a cross wall having a central aperture through which the cutting tool extends slidably.

A still further object of the invention is to provide a rivet removing device which effectively and efficiently fulfills its intended purpose, is so designed and constructed that it may be produced at a low cost, and embodies simple and novel means for detachably connecting the arbor to the operating end of the rivet gun.

Other objects of the invention and the various advantages and characteristics of the present rivet removing device will be apparent from a consideration of the following detailed description.

The invention consists in the several novel features which are hereinafter set forth and are more particularly defined by the claims at the conclusion hereof.

In the drawing which accompanies and forms a part of the present disclosure or specification and in which like numerals of reference denote corresponding parts throughout the several views:

Figure 1 is a side view of a rivet removing device embodying the invention;

Figure 2 is a longitudinal section of the device, illustrating in detail the construction of the cutting tool and showing the design and manner of mounting of the spring loaded sleeve-like jacket that constitutes the means for retracting the arbor after a rivet removing operation;

Figure 3 is a front view of the device, showing in detail the manner in which the centrally apertured cross wall at the outer or front end of the jacket serves to support and guide the cutting tool; and

Figures 4, 5 and 6 are enlarged fragmentary sections illustrating the manner in which the device operates to remove a rivet from a pair of riveted plates.

The device which is shown in the drawing constitutes the preferred form or embodiment of the

invention, and, as described in detail hereafter, serves as a medium or instrumentality for removing a rivet 7 from a pair of abutting plates 8. It is adapted for use in connection with, and to be attached to the operating end of, a conventional or standard pneumatic rivet gun (not shown) and as its principal components or parts comprises an arbor 9, a cutting tool 10, and a sleeve-like jacket 11. As shown in Figure 4, the rivet 7 embodies a cylindrical shank 7a which extends through a pair of registering holes 8a in the plates 8 and has at one end thereof a preformed head 7b with a dimple 7c in the center thereof, and at its other end an upset head 7d. When the rivet is in place the two heads abut, respectively, against the outer faces of the plates 8 and serve, as well understood in the art, to hold the plates in clamped relation.

The arbor 9 of the device is formed of any suitable metal stock of circular cross section and has at one end thereof a reduced shank 12 which is shaped to fit loosely in the nozzle of the rivet gun and is of such length that when the device is in connected relation with the gun it is disposed in the path of the reciprocating hammer of the gun and receives the successive impulses or hammer blows of the hammer. A helical spring 13 of greater diameter than the shank 12 surrounds, and is arranged in concentric relation with, the shank and serves detachably to connect the device to the rivet gun. This spring is adapted to interfit with, and be screwed onto, the usual external screw thread on the nozzle of the rivet gun. The front end of the spring 13 is tapered and has the extremity thereof suitably anchored to the inner portion of the shank 12. When it is desired to connect the device to the rivet gun the shank 12 is first inserted into the nozzle of the gun. Thereafter the arbor 9 is rotated in order to bring the spring 13 into screw threaded engagement with the external screw thread on the gun nozzle. To remove the device it is only necessary reversely to turn or rotate the arbor. The other or front end of the arbor is provided in the extremity thereof with a cylindrical socket 14. As shown in the drawing, this socket extends lengthwise of, and is in coaxial relation with, the arbor.

The cutting tool 10 is cylindrical. It is preferably formed of hard metal and is substantially the same in diameter as the socket 14. One end of the cutting tool 10 fits within the socket 14 and is held in connected relation with the front end of the arbor 9 by way of a set screw 15 which, as shown in Figure 2, extends through a transverse screw threaded hole 16. The latter is formed in the front end of the arbor and communicates with the central portion of the socket 14. The diameter of the cutting tool 10 is slightly less than the diameter of the rivet holes 8a in the plates 8. The front end face of the cutting tool is provided with a circular groove 17 which is semi-circular in cross section and serves to form outwards thereof an annular cutting edge 18 at the front end of the cutting tool. In connection with use of the device, the cutting edge 18 is placed against the central portion of the preformed head 7b of the rivet 7 while the arbor 9 is held in coaxial relation with the shank of the rivet. After properly positioning the cutting edge, the rivet gun is actuated so as to effect hammering of the arbor 9. During hammering of the arbor the cutting edge 18 penetrates through the central portion of the preformed head 7b of the rivet 7 and operates to sever the outer portion of

such head from the rivet shank 7a. As soon as the outer portion of the preformed head of the rivet is severed from the shank by the cutting edge 18, additional or further hammering of the arbor results in the front end face of the cutting tool 10 ejecting the shank of the rivet from the rivet holes 8a in the plates 8. The cutting tool is of such length that in connection with hammering of the arbor it will pass completely through the rivet holes 8a as shown by dotted lines in Figure 5. The central portion of the outer end face of the cutting tool, that is, the portion within the circular groove 17, is shaped to form a pilot point 19. This point projects beyond or outwards of the cutting edge 18 and is adapted when the device is manipulated into its operative position to fit within the dimple 7c in the preformed head 7b of the rivet and maintain the cutting edge in centered relation with the preformed head. In the event that the device is used to remove a rivet having no dimple, the pilot point 19 serves to form a dimple in the center of the head and thus maintain the cutting edge 18 in centered relation with the head. The sleeve-like jacket 11 surrounds, and is in sliding engagement with, the front end of the arbor 9 and together with a helical compression spring 20 serves to retract the arbor from the plates 8 after a rivet removing operation. It is preferably formed of metal and has at the front end thereof an integral cross wall 21. The latter is adapted in connection with use of the device to fit against the preformed head 7b of the rivet 7, and has in the central portion thereof a substantially circular aperture 22 in which the outer end of the cutting tool is slidably mounted. The compression spring 20 surrounds the central portion of the arbor 9 and has one end thereof in abutment with the inner or rear end of the sleeve-like jacket 11. The other end of the spring extends through, and is held by a drive fit in, a transverse hole 24 in the arbor. Prior to penetration of the cutting edge 18 of the cutting tool into the preformed head of the rivet the spring 20 is in its extended condition and the cross wall 21 at the front end of the jacket 11 is disposed directly behind the cutting edge. In connection with a rivet removing operation in the jacket 11, after abutment of the cross wall 22 against the preformed head of the rivet, remains stationary and the arbor and cutting tool move forward relatively to the jacket. During forward movement of the arbor and tool the spring 20 is compressed. When the device after a rivet removing operation is released the spring 20 extends or expands and operates automatically to effect retraction of the arbor and cutting tool. The upper portion of the cross wall 21 is provided with a V-shaped notch 25 which leads to, and intersects, the circular aperture 22 and enables the user of the device readily to observe the front end of the cutting tool 10 during application thereof to the central portion of the preformed head of the rivet. The front upper portion of the sleeve-like jacket 11 is provided with a cutout 26 and this extends rearwards from the upper portion of the cross wall 21 and permits the user of the device to see through the notch 25. Forward sliding movement of the jacket relatively to the arbor 9 is limited by way of a stop pin 27. This pin has one end thereof disposed in a socket 28 in the upper front portion of the arbor 9 and is adapted to be engaged by the portion of the sleeve-like

jacket 11 that defines the rear end of the cut-out 26.

When it is desired to use the device the arbor is manipulated into a position wherein the pilot point 19 is disposed in the dimple 7c in the center of the preformed head 7b of the rivet 7. After so manipulating the arbor and while the arbor is maintained at right angles to the plate, the rivet gun to which the device is attached is actuated. As soon as the gun is started the arbor is hammered forwards with the result that the annular cutting edge 18 penetrates through the preformed head 7b and severs the outer portion of the head from the shank of the rivet. Directly upon severance of the outer portion of the preformed head from the rivet shank, the outer end face of the cutting tool in connection with further forward movement of the arbor ejects the shank 7a of the rivet from the rivet holes 8a in the plates 8. During forward travel or movement of the arbor and cutting tool the sleeve-like jacket 11 remains stationary so long as the cross wall 21 thereof is in abutment with the preformed head 7b of the rivet. When the device is released after removal of the rivet 7 the jacket 11 and the spring 20 operate to retract the arbor and cutting tool as hereinbefore pointed out. When the device is removed from the plates the severed outer portion of the preformed head of the rivet drops. It is contemplated that during a rivet removing operation the upset head of the rivet will be surrounded by any suitable backing bar (not shown).

The herein described rivet removing device is highly efficient in operation and operates to remove a rivet in an exceedingly short period of time. When properly used the device will remove a rivet without enlarging or distorting the rivet holes in the riveted plates. Because of this particular feature it is possible after the device has been used to remove a damaged or faulty rivet to apply a similar sized rivet in its stead. Because the device is essentially simple in design it may be manufactured at a low cost. The subject device is capable of removing all forms or types of rivets including rivets having countersink variety preformed heads.

The invention is not to be understood as restricted to the details set forth since these may be modified within the scope of the appended claims without departing from the spirit and scope of the invention.

Having thus described the invention what I claim as new and desire to secure by Letters Patent is:

1. A device adapted in conjunction with a rivet gun to remove a head-equipped rivet from a plurality of abutting plates with registering circular holes therethrough for the shank of the rivet, and comprising an elongated arbor having one end thereof shaped to fit within the nozzle of the rivet gun and extend into the path of the gun hammer and provided with means for yieldingly holding it in connected relation with the gun nozzle, and a cylindrical cutting tool of less diameter than the holes in the plates, connected to the other end of the arbor, extending lengthwise of said arbor, having in its outer end face a concentric annular groove defining outwards thereof an annular cutting edge for placement against the central portion of the head of the rivet, and adapted when said cutting edge is placed in centered relation with the head of the rivet and the arbor is subjected to hammer blows by the gun to sever the outer portion of the rivet head from

the rivet shank and eject the shank from the holes in the plate.

2. A device adapted in conjunction with a rivet gun to remove a head-equipped rivet from a plurality of abutting plates with registering holes therethrough for the shank of the rivet, and comprising an elongated arbor having one end thereof shaped to fit within the nozzle of the rivet gun and extend into the path of the gun hammer and provided with means for yieldingly holding it in connected relation with the gun nozzle, and a cutting tool of less width than the holes in the plates, connected to the other end of the arbor, extending lengthwise of said arbor, having on the outer end face thereof a continuous cutting edge for placement against the central portion of the head of the rivet and in addition a centrally disposed pilot point projecting outwards of the cutting edge, and adapted when said cutting edge is placed in centered relation with the head of the rivet and the arbor is subjected to hammer blows by the gun to sever the outer portion of the rivet head from the rivet shank and eject the shank from the holes in the plate.

3. A device adapted in conjunction with a percussion type rivet gun to remove a head-equipped rivet from a plurality of abutting plates with registering circular holes therethrough for the shank of the rivet, and comprising an elongated arbor having one end thereof shaped to fit within the nozzle of the rivet gun and extend into the path of the gun hammer and provided with means for yieldingly holding it in connected relation with the gun nozzle, and a cylindrical cutting tool of less diameter than the holes in the plates, connected to the other end of the arbor, extending lengthwise of said arbor, provided in its outer end face with a concentric circular groove defining outwards thereof an annular cutting edge for placement against the central portion of the head of the rivet, having the portion thereof within the groove shaped to form a pilot point extending outwards of the cutting edge, and adapted when said cutting edge is placed in centered relation with the head of the rivet and the arbor is subjected to hammer blows by the gun to sever the outer portion of the rivet head from the rivet shank and eject the shank from the holes in the plate.

4. A device adapted in conjunction with a rivet gun to remove a head-equipped rivet from a plurality of abutting plates with registering circular holes therethrough for the shank of the rivet, and comprising an elongated arbor having one end thereof shaped to fit within the nozzle of the rivet gun and extend into the path of the gun hammer and provided with means for yieldingly holding it in connected relation with the gun nozzle, a cylindrical cutting tool of less diameter than the holes in the plates, connected to the other end of the arbor, extending lengthwise of said arbor, having in its outer end face a concentric annular groove defining outwards thereof an annular cutting edge for placement against the central portion of the head of the rivet, and adapted when said cutting edge is placed in centered relation with the head of the rivet and the arbor is subjected to hammer blows by the gun to sever the outer portion of the rivet head from the rivet shank and eject the shank from the holes in the plate, and means for retracting the arbor and tool after a rivet removing operation, consisting of a sleeve-like jacket mounted on said other end of the arbor to slide longitudinally to a limited extent and provided at its

outer end with a cross wall adapted in connection with a rivet removing operation to abut against the head of the rivet and having in the central portion thereof an aperture through which the tool extends slidably, and a spring mounted on the arbor and arranged to urge the jacket outwards relatively to said arbor.

5. A device adapted in conjunction with a rivet gun to remove a head-equipped rivet from a plurality of abutting plates with registering circular holes therethrough for the shank of the rivet, and comprising an elongated arbor provided on the central portion thereof with an abutment forming element and having one of its ends shaped to fit within the nozzle of the rivet gun and extend into the path of the gun hammer and embodying means for yieldingly holding it in connected relation with the gun nozzle, a cylindrical cutting tool of less diameter than the holes in the plates, connected to the other end of the arbor, extending lengthwise of said arbor, having in its outer end face a concentric annular groove defining outwards thereof an annular cutting edge for placement against the central portion of the head of the rivet, and adapted when said cutting edge is placed in centered relation with the head of the rivet and the arbor is subjected to hammer blows by the gun to sever the outer portion of the rivet head from the shank and eject the shank from the holes in the plate, and means for retracting the arbor and tool after a rivet removing operation, consisting of a sleeve-like jacket mounted on said other end of the arbor to slide longitudinally to a limited extent and provided at the outer end thereof with a cross wall adapted in connection with a rivet removing operation to abut against the head of the rivet and having in the central portion thereof an aperture through which the tool extends slidably, and a helical compression spring extending around the central portion of the arbor, having one end thereof in abutment with the aforementioned element and its other end in abut-

ment with the inner end of the jacket, and arranged to urge the jacket outwards relatively to said arbor.

6. A device adapted in conjunction with a rivet gun to remove a head-equipped rivet from a plurality of abutting plates with registering circular holes therethrough for the shank of the rivet, and comprising an elongated arbor having one end thereof shaped to fit within the nozzle of the rivet gun and extend into the path of the gun hammer and provided with means for yieldingly holding it in connected relation with the gun nozzle, a cylindrical cutting tool of less diameter than the holes in the plates, connected to the other end of the arbor, extending lengthwise of said arbor, having in its outer end face a concentric annular groove defining outwards thereof an annular cutting edge for placement against the central portion of the head of the rivet, and adapted when said cutting edge is placed in centered relation with the head of the rivet and the arbor is subjected to hammer blows by the gun to sever the outer portion of the rivet head from the rivet shank and eject the shank from the holes in the plate, and means for retracting the arbor and tool after a rivet removing operation, consisting of a sleeve-like jacket mounted on said other end of the arbor to slide longitudinally to a limited extent and provided at its outer end with a cross wall adapted in connection with a rivet removing operation to abut against the head of the rivet and having in the central portion thereof an aperture through which the tool extending slidably, and a spring mounted on the arbor and arranged to urge the jacket outwards relatively to said arbor, said jacket being provided in its cross wall with a V-shaped notch leading to the aperture and having a cutout communicating with, and leading rearwards from, the notch in order to permit the user of the device readily to view the tool.
